UNITED STATES PATENT OFFICE.

ERNEST DAVIS, OF SYRACUSE, NEW YORK, ASSIGNOR TO THE PROSPERITY COMPANY INC., OF SYRACUSE, NEW YORK, A CORPORATION OF NEW YORK.

DRYING-ROOM TUMBLER.

Application filed June 23, 1927. Serial No. 200,981.

This invention relates to drying room tumblers of the type described in my pending application Sr. No. 183,195, filed April 12, 1927, and has for its object a construction by which the drying is facilitated by a slow current or change of air created by the piston or pumping action of the oscillating clothes support with the clothes thereon.

The invention consists in the novel features and in the combinations and constructions hereinafter set forth and claimed.

In describing this invention, reference is had to the accompanying drawings in which like character designate corresponding parts in all the views.

Figure 1 is a lengthwise vertical sectional view of this tumbler or drier.

Figure 2 is a vertical cross-sectional view.

Figure 3 is an enlarged fragmentary sectional view of the clothes support and the contiguous part of the cylindrical body.

Fig. 4 is a detail of the inlet damper.

This drying room tumbler comprises a cylindrical body arranged with its axis horizontal, an oscillating support mounted in the body to oscillate above and below the horizontal plane of the axis of the body, the support being mounted coaxially with the body and means by which a heated current of air is drawn by the suction action of the support when oscillating in one direction into the body and is held from movement out of the body during the oscillation of the support in the other direction whereby it is compressed and forced through the clothes on the support.

1 designates the body which is cylindrical in general form and mounted upon a suitable hollow base 2 which encloses the air chamber 3 to be presently described.

4 is the oscillating support mounted on a shaft 5 arranged coaxially in the body 1 and connected at one end to a suitable actuating mechanism designated generally by the reference numeral 6.

5 The body 1 has a suitable cover 7 at its top for permitting the clothes to be inserted and removed. The support 4 is mounted to oscillate in opposite directions above and below the horizontal plane of the axis of the shaft 5 and is provided with openings through which the air can pass during the oscillating action. These openings are provided by forming the intermediate portion of the support 4 of wire mesh 8. This support is a sheet metal frame and has a hub 9 on the

shaft 5. The support slidably fits the peripheral and end walls of the body 1, so that the support acts as a piston to draw in and compress the air during the oscillations thereof and it is formed at its margins with spring 60 pressed packings 10 which are pressed outwardly by springs 11 against the walls of the body 1. The packing and springs are located between the upper and lower sheet frame metal pieces 12 of the support.

65 The support is also formed with deflectors 13 extending lengthwise of its upper side parallel to the axis of the shaft 5 and located near said axis, these deflectors preferably having downwardly inclined sides so as to cause the clothes to turn over when tumbling from one side of the shaft to the other.

70 The walls of the hollow base 2 have tapering extensions 14 extending into the body 1 forming a hollow partition in the lower half 75 of the body 1 and heating coils 15 are located in the air chamber. The air chamber has a suitable inlet 16 for air which can be partly or wholly closed by a closure 17. One of the walls 14 is formed with holes 18 therethrough 80 and the other wall is formed with a comparatively large opening 19 closed by a check valve 20 which opens into the interior of the body 1. A breather opening 21 is located in the upper portion of the body.

85 In operation, the clothes are placed on the support and during the oscillation thereof, will be thrown from one side to the other of the shaft 5, the baffle 13 causing them to turn over during the tumbling operation. During 90 the oscillating movement to the left, Figure 2, the clothes will be thrown from the right hand side of the support to the left hand side and during the first part of such movement, the right hand side of the support will act 95 during its upward movement as a piston to draw air through the holes 18 and when the support reaches the dotted line position, Figure 2, the clothes will be thrown and turned over onto the left hand side of the support 100 which is in its down or dotted line position, Figure 2. Now, during the reverse operation, at which time the left hand side of the support with the clothes thereon moves upwardly, this left hand side with the clothes 105 thereon forms a piston to draw air in past the flap valve 20 until the clothes tumble from the left hand side to the right hand side of the support. During the next reverse operation, the support with the clothes thereon 110

which have tumbled from the right hand side to the left hand side of the support compresses the portion of this air against the flap valve causing the air to pass through the clothes 5 on the left hand side of the support and during the upward movement of the left hand side of the support some of the air that has passed through the clothes will be forced out through the breather opening. Thus, 10 during each oscillation of the support, some new dry air is drawn into the body and passed through the clothes and some of the moisture laden air above the clothes passes out through the breather opening. Thus, a slow but effective 15 circulation or change of air is effected. The air pressed by the right hand side of the support with the clothes thereon back into the air chamber 3 is dried and passes out past the flap valve. The closure 17 is opened far 20 enough to supply enough air to the air chamber to compensate for that displaced out of the air chamber by the suction action of the support with the clothes thereon.

What I claim is:

- 25 1. A drying room tumbler comprising a horizontal cylindrical body, an oscillating support mounted in the body to oscillate about the axis of the body above and below the horizontal plane of such axis, the support having air passages therethrough and slidably fitting the body whereby it acts with the clothes thereon as a rotary piston, an air chamber extending into the lower part of the body and having a check valve controlled outlet into the body arranged to prevent passage of air under the suction action of the support with the clothes thereon from the body into the air chamber.
- 30 2. A drying room tumbler comprising a horizontal cylindrical body, an oscillating clothes support mounted in the body to oscillate about the axis of the body above and below the horizontal plane of such axis, the support having air passages therethrough and slidably fitting the body whereby it acts with the clothes thereon as a rotary piston, an air chamber extending into the lower part of the body and having a check valve controlled outlet into the body arranged to prevent passage of air under the suction action of the support with the clothes thereon from the body into the air chamber and a breather opening located in the upper part of the body.
- 35 3. A drying room tumbler comprising a

horizontal cylindrical body, an oscillating clothes support mounted to oscillate in the body about the axis thereof above and below the horizontal plane of said axis and having air passages therethrough, the oscillating support slidably fitting the walls of the body whereby the support during the oscillation thereof acts as a rotary piston, an air heating chamber extending into the lower part of the body and having the wall on one side formed with holes therethrough and the wall on its other side provided with a check valve for permitting air to pass from the heating chamber into the body and prevent it from passing back from the body into the heating chamber.

4. A drying room tumbler comprising a horizontal cylindrical body, an oscillating clothes support mounted to oscillate in the body about the axis thereof above and below the horizontal plane of said axis and having air passages therethrough, the oscillating support slidably fitting the walls of the body whereby the support during the oscillation thereof acts as a rotary piston, an air heating chamber extending into the lower part of the body and having the wall on one side formed with holes therethrough and the wall on its other side provided with a check valve for permitting air to pass from the heating chamber into the body and prevent it from passing back from the body into the heating chamber, the body being formed with a breather opening in the upper part thereof.

5. A drying room tumbler comprising a horizontal cylindrical body, an oscillating clothes support mounted in the body about the axis thereof above and below the horizontal plane of said axis and having a deflector extending lengthwise thereof parallel to its axis and located near and on each side of its axis.

6. A drying room tumbler comprising a cylindrical body, an oscillating clothes support mounted in the body about the axis thereof above and below the horizontal plane of said axis and having a deflector extending lengthwise thereof parallel to its axis and located near and on each side of its axis, said deflector having inclined side faces.

In testimony whereof, I have hereunto signed my name, at Syracuse, in the county of Onondaga, and in the State of New York, this 12 day of May, 1927.

ERNEST DAVIS.
